HOLDER FOR IRONING BOARD COVER
OR THE LIKE

Alma L. Howell, 14313 Lanning, Whittier, Calif.

Filed July 24, 1962, Ser. No. 71,035

Term of patent 14 years

(Cl. D17—3)

Fig. 1.

Fig. 2.

Fig. 3.

Fig. 4.

FIG. 1 is a perspective view of a holder for ironing board cover or the like, showing my new design;

FIG. 2 is an edge or side view thereof;

FIG. 3 is a view of the side opposite that seen in FIG. 1; and

FIG. 4 is an end view.

I claim:

The ornamental design for a holder for ironing board cover or the like, as shown.
